(57) **CLAIM**

The ornamental design for a tubing sealer with protruding sealing head, as shown and described.

DESCRIPTION

FIG. 1 is a right front isometric view of a tubing sealer with protruding sealing head showing our design;

FIG. 2 is a front elevational view thereof;

FIG. 3 is a right side elevational view thereof, the left side elevational view being a mirror image;

FIG. 4 is a top view thereof;

FIG. 5 is a bottom view thereof; and,

FIG. 6 is a rear elevational view thereof.
